UNITED STATES PATENT OFFICE.

JOHN F. OHMER AND ALBERT S. WHEELBARGER, OF DAYTON, OHIO, ASSIGNEES TO OHMER FARE REGISTER COMPANY, OF DAYTON, OHIO, A CORPORATION OF NEW YORK.

FEEDING MEANS FOR PRINTING MACHINES.

Application filed October 22, 1926. Serial No. 143,324.

The object of this invention is to provide an improved feeding means for printing matter, and is an improvement on that type of machine as shown in the application of 5 Wheelbarger and Coil 65,532, filed October 29, 1925.

It has been noted that the printed paper occasionally meets with some obstruction and that in previous devices of this kind the 10 paper ceases to move at its proper rate with the result that the machine becomes jammed and inoperative. The object of this invention is to overcome such an objection.

More specifically, the invention relates to 15 an improved feeding means in which an electrotype extends partly around a printing drum, which electrotype is provided with corrugated extensions which span the gap between the sides of the electroplate. Another object of the invention is to provide 20 means to remove the inking means out of contact with such corrugations as the electrotype rotates, so that the corrugated surface of the electrotype will not be inked, 25 and will, therefore, not soil or deface the paper.

Referring more specifically to the drawings;

Fig. 1 is a front elevational view of the 30 machine showing a part of the printing mechanism.

Fig. 2 is a cross-sectional view on the line 2-2 of Fig. 1, and in addition shows a part 35 of the actuating mechanism for the platens, inking rollers and electrotype.

Fig. 3 is a plan view of the electroplate before it is curved to be placed on the rotating roller which normally supports the same, and

40 Fig. 4 represents one of the tickets as printed by the machine.

Referring more particularly to the drawings in which like reference characters are used throughout to denote similar parts;

45 The printing disks 1 are actuated by the operator through handles or finger pieces 2 mounted on gears 3 rotatably mounted on the shaft 4, which gears 3 mesh with pinions 5 carried by the printing disks 1. The 50 printing disks 1 are provided with numerals from zero to nine inclusive, and certain of the wheels are provided with other indicia such as names of the months and appropriate classes of fare, such as ticket, commuta-

tion, etc., as fully described in said application of Wheelbarger and Coil 65,532. The printing disks 5 print the last line appearing on the ticket as represented in Fig. 4, which line of printing indicates that the ticket was issued on September 7, 1925, from 55 station 224 to station 995. The "D" between the last mentioned numbers indicates that the car was traveling "down". This letter might have been east, west, north, south or other appropriate designation to indicate 60 the direction in which the car was traveling. This line of printing further indicates that the passenger handed to the conductor a ticket, which ticket was worth \$3.34, and that 65 2,566 passengers had been carried by that 70 car.

The last line on the ticket is printed by means of a platen 6 carried by an oscillating member 7 actuated by a pitman 8, which has one end connected with a gear 9 rotated 75 by a gear 10, which is actuated by the operating handle 11. The oscillating member 7 also carries an inking roller 12 and a platen 13. A ticket strip 14 passes over the platen 6 and a record strip (not shown) passes over 80 the platen 13. The above described mechanism serves as a means to cause the ticket strip and the record strip to be brought into contact with the said printing wheels 85 1 each time the operating crank 11 is properly actuated. After the ticket strip 14 passes over the platen 6, it passes between the platen 15 and an electroplate 16. The platen 15 is mounted on a shaft 17, and the electroplate 16 is mounted on a drum 21 90 mounted on the shaft 18. The shafts 17 and 18 are mounted in the sidewalls of the machine and provided with gears 19 and 20 respectively, which gears mesh with and are 95 driven by the gear 9.

The electroplate 16, as shown in Fig. 3, is provided with suitable type to indicate instructions or regulations, or other printed matter, but in the specific instance shown the printed matter relates to a transportation ticket. This electrotype is provided with cutaway portions 22, and between said cutaway portions 22 are corrugated surfaces 23 of such a length that when the electroplate 16 is curved into the form of a circle 100 105 and placed on the drum 21, the corrugated surfaces 23 will extend to the opposite side of the electroplate 16. With such a con-

struction, the ticket strip 14 is constantly engaged either by the printing type or the corrugated surfaces, and, therefore, its feed is always positive regardless of whether or not the electroplate is printing. Obviously, these corrugated surfaces 23 would be also inked by the inking roller 24, unless some means were provided to prevent such an occurrence, and if the corrugated surfaces 23 were inked it would deface the lower part of the ticket or the last line thereof so that the ticket would be practically useless, for it would probably be unreadable.

Means have, therefore, been provided to remove the inking roller 24 from the electroplate when the corrugated surfaces 23 are beneath the inking roller 24. Cams 25 are carried by the opposite ends of the drum 21, which cams engage circular plates 26 on opposite sides of the inking roller 24, which inking roller is mounted on a shaft 27 journaled in the sidewalls of the machine. Springs 28 are interposed between the shaft 27 and a plate 29 secured to the machine, which springs 28 perform the function of urging the shaft 27 and inking roller 24 toward the electroplate. The cams 25 are in alignment with the corrugated surfaces 23 and, therefore, each time the shaft 18 rotates the inking roller 24 is moved away from the electroplate 16 by means of the cams 25 and circular plates 26. This occurs when the corrugated surfaces 23 are beneath the inking roller 24.

As shown in the said application of Wheelbarger and Coil 65,532, the ticket strip after being printed passes a knife where the printed portion is severed from the remainder of the strip and is issued to a passenger. It is a well-known fact that many machines which issue tickets, receipts and the like will become clogged and inoperative if a finger is pressed over the exit of said ticket, which results in the ticket not being issued and holding back subsequent tickets which clog the machine and render it inoperative. It is apparent that with the improvements indicated in this ap-

plication the ticket will at all times be positively fed so as to eliminate the possibility of the machine becoming inoperative because of the non-continuous feed of the ticket strip.

Obviously, many modifications may be made in the specific form shown or illustrated by way of example in this application and it is therefore desired to claim the invention broadly in whatever form it may be embodied.

Having now described our invention, we claim:

1. In a machine of the class described, a printing means consisting of a drum, an electrotype, said electrotype being provided with corrugated extensions, said electrotype and extensions extending completely around said drum, an inking means for the type on said electrotype, and means whereby said inking means is moved away from said drum when said extensions are adjacent to said inking means.

2. In a machine of the class described, means whereby a ticket may be printed from two sets of type, one of said sets of type being an electroplate, a drum on which said electroplate is mounted, said electroplate extending for only a portion of the circumference of said drum, feeding means interposed on said drum between the edges of the electroplate, said feeding means completing the circumference of said drum, inking means whereby the type on said electroplate are inked, and means whereby said inking means are rendered inoperative when said feeding means are adjacent said inking means.

3. In a machine of the class described, an electroplate consisting of a plate on which are printing type, and corrugated extensions projecting from said plate and forming a part thereof.

In testimony whereof we affix our signatures.

JOHN F. OHMER.
ALBERT S. WHEELBARGER.
